UNITED STATES PATENT OFFICE.

FRANK L. CROCKETT, OF NORTH UXBRIDGE, MASSACHUSETTS, ASSIGNOR TO WHITIN MACHINE WORKS, OF WHITINSVILLE, MASSACHUSETTS, A CORPORATION OF MASSACHUSETTS.

TOP-COMB MOTION.

1,221,839.

Specification of Letters Patent. Patented Apr. 10, 1917.

Application filed August 12, 1916. Serial No. 114,501.

To all whom it may concern:

Be it known that I, FRANK L. CROCKETT, a citizen of the United States, residing in North Uxbridge, Massachusetts, have invented the following-described Improvements in Top-Comb Motions.

The invention concerns the operation of combing machines of the kind employing top combs which are depressed into engagement with the tuft and more especially those which are quickly depressed to a full penetration into the tuft. This invention is more specifically an improvement in the top comb motion disclosed in the prior application of 15 G. M. Whitin, filed February 14, 1914, Serial No. 818,616. As illustrated in the drawings of that application, all the top comb arms of a multi-head comber are carried on a single longitudinal shaft, known as the 20 top comb shaft, and lifted from the path of the tuft by a cam arm applied to one end of said shaft engaged and lifted by a rotary cam disk. When the arm rides off the abrupt shoulder of the cam, it, and all the top 25 comb arms are caused to drop quickly to their lowest position, the cam arm striking the bottom of the cam notch and the top combs striking their several abutments all at about the same instant. Such quick de- 30 scent of the top combs, occurring at the appropriate point in the combing cycle, produces numerous advantages fully explained in the said application and now availed of very generally in commercial practice. The 35 quickness of the descent is important, but is not attained without a considerable vibration in the machine, arising from the contact with the several abutments, and there is also a tendency to torsional strains in the 40 comb shaft, due to its length and the load on it, which gives rise to a tendency to rebound at the lowest position and which has heretofore been attempted to be counteracted by a counter-weight applied to the 45 far end of the shaft. The present invention provides the means for eliminating the serious vibration and also the need for the counter-weight and also greatly improves the general action of the motion, permitting 50 higher speeds with satisfactory operation. It consists in the application to the comb shaft of an elastic or yielding shaft coupling, preferably interposed between the end of the shaft that is operated by the quick 55 descent mechanism and usually in the drive-

head of the machine, and the series of top comb arms which, as will be understood, are distributed along the length of the top comb shaft. The particular style of coupling is believed to be not important, provided it possesses the requisite elasticity, and the one which is preferred and shown herein is old and well-known in principle. Its effect is believed to be accomplished by virtue of its localization of the point of greatest torsion, which tends to eliminate torsional vibration elsewhere throughout the length of the shaft, and at the same time by the accommodation it affords to the cam and top comb arms with respect to the time of their engagement with their respective abutments.

In the drawings—

Figure 1 is an end view of the top comb shaft showing the quick descent mechanism and the top comb arms in elevation and the adjacent part of the framework of a Heilmann type comber;

Fig. 2 is a portion of the same type of machine in top plan showing the location of the elastic coupling, and

Fig. 3 is a larger scale axial section of the preferred coupling.

The top comb shaft 1 will be understood to be journaled in the several frame uprights 2, and to extend through all of the eight or more combing heads of the machine, carrying a pair of top comb arms 3 for each head, extending forwardly therefrom and carrying the top combs 4 at their extreme forward ends. Each arm has a lateral finger carrying an abutment screw 5, which engages one of the fixed abutments 6 to limit the descent of the combs. The shaft is rocked in a journal bearing by the cam arm 7, which rests by its wear-piece 8 upon the edge of the disk cam 9, the latter being fast on the comb cylinder shaft as indicated. It will be apparent that the rotation of the cam will gradually lift the top comb arms 10 until the passage of its abrupt shoulder 10 beneath the cam arm 7 allows all of the arms to drop, thus producing the quick depression of the top combs above referred to. However, it will be understood that this is only 105 one means of obtaining such a depression and that other means may be employed within this invention.

The elastic coupling is applied between the hub of the cam lever 7 and the top comb 110

shaft and consists of two sleeve members 11 and 12, one of which (11) is firmly set-screwed to the shaft, and the other (12) is free to turn slightly thereon, being formed 5 for convenience as the hub of the arm 7, and slit as shown, and provided with a clamp bolt 13 whereby it may be set to turn snugly on the shaft without lost motion. Each member 12 and 11 is bored and counter-bored at intervals around their common 10 axis and parallel with such axis, and a series of spring steel pins 14 are driven into the registering holes, thereby connecting the two sleeves with each other and by means of 15 an annular series of spring members which permit resilience between the lever and the shaft in an angular or torsional direction. The flexing of the spring members is accommodated by the clearances provided by the 20 counter-bored portions 14^a of the holes in the members, such portions being, as shown in Fig. 3, at the proximate ends of the holes. The dimensions and number of these spring pins are subject to variation according to

the lengths of the top comb shafts, the 25 weight and length of the top combs and their arms, and other obvious considerations, and are necessarily left for determination according to the characteristics of the 30 combing machines on which the invention is to be employed.

Claims:

1. A top comb motion for combing machines, comprising the combination of the top comb shaft carrying the top combs 35 thereon and means for oscillating said shaft, of an elastic coupling between said means and the top comb.
2. A top comb motion for combing machines, comprising in combination with the 40 top comb shaft having the top combs thereon and quick depression mechanism for said combs, of an elastic shaft coupling between said mechanism and the top combs.

In testimony whereof, I have signed this 45 specification.

FRANK L. CROCKETT.
